DESIGN FOR A NOISE MAKING TOY AIRPLANE

Louis J. Ripich, Cleveland, Ohio

Application April 20, 1939, Serial No. 84,437

Term of patent 7 years

To all whom it may concern:

Be it known that I, Louis J. Ripich, a citizen of the United States, residing at 12501 Lenecrave Avenue, in the city of Cleveland, county of Cuyahoga, and State of Ohio, have invented a new, original, and ornamental Design for a Noise Making Toy Airplane, of which the following is a specification, reference being had to the accompanying drawing, forming a part thereof.

I claim:

The ornamental design for a noise making toy airplane, substantially as shown.

LOUIS J. RIPICH.
